APPARATUS FOR OPERATING UPON LABELS.

Application filed December 1, 1922. Serial No. 604,282.

The invention relates to apparatus for operating upon labels; and particularly to apparatus for accurately feeding continuous label tapes or strips successive portions of which are to be used as labels, cutting off the individual label portions, and thereafter moving the same into position for further operations to be performed thereon.

The invention is directed, in its preferred embodiment, to the provision of devices for feeding tape of woven fabric on which labels are printed successively, and for operating upon the labels prior to the sewing of the same upon articles of clothing or other goods. In some aspects of the invention, however, tape on which the successive label indicia are woven, or otherwise formed, rather than printed, may be operated upon. And in some aspects of the invention the accurate feeding of the printed tape may be for a different purpose from that of presenting the same properly registered, to a cutter, such as for the purpose of properly registering the tape, unsevered, with printing apparatus for printing further matter thereon. In the preferred form of the invention, however, the same constitutes a part of or an adjunct to a sewing machine, in which individual labels are cut off from the tape and fed into position to be sewed on articles, and are thus sewed, successively.

Great difficulty has previously been experienced, where label tape is to be fed forward to a cutter or to other means requiring alignment, in obtaining accurate registration. This is for the reason that such tape is liable to stretch more or less. A slight error in each label length fed, or in some of the same, naturally results in a multiplied error throughout the length of a tape, so that automatic feed in such a case might well result in a label being cut off in the middle of the printed matter.

When it has been proposed to provide devices for feeding the tape, cutting off individual labels, folding the same and sewing them on articles successively, the difficulties in the way of automatic operation have been such as heretofore to prevent practical success.

The functions referred to are successfully achieved in our invention. A tape is used having what may be termed an abutment thereon between each pair of individual labels. In the case of a printed label, in

the form of the invention specifically illustrated, the tape is provided with transverse slits between the labels, which constitute such abutments. A reciprocating member slides forwardly over the tape, from a point a short distance to the rear of a slit, engages the slit, and moves the tape forwardly to the end of the forward stroke of the member. Thereby the slits are positioned successively with certainty at a predetermined point, regardless of any slight variations in length of the label sections, either caused by stretching of the tape etc., subsequent to the printing of the labels, or because of inaccuracies in the forming of the slits. The front label 60 may be cut off from the tape, after each slit has been thus positioned, by properly timed means acting at a point intermediate the first and second labels, and preferably at 65 or adjacent to the said point at which the slit has been positioned by the reciprocating feeding member. This point being always established at the rear edge of the severed front label, the position of the front label 70 itself will be invariable at this time, with 75 respect to the fixed bed of the machine. Accordingly other devices may accurately engage the label and perform other operations thereon in timed sequence, such as bending the ends thereof and properly positioning it 80 for movement into position to be machine sewed, around the edges thereof, to a garment. 85

Objects of the invention comprise the provision of simple and effective devices of the 90 character indicated. The invention consists in the novel construction, arrangement and combination of parts hereinafter described, according to the preferred embodiments thereof. The invention will be more particularly pointed out in the appended claims. 95

In order that the invention may be more clearly understood attention is hereby directed to the accompanying drawings, illustrating one form of apparatus embodying the invention. In the drawings

Fig. 1 is a perspective view of a machine for sewing labels on garments containing our invention, showing the same position 100 of the parts as Fig. 3, the machine being viewed from one side;

Fig. 2 is a perspective view of the same machine viewed from the other side;

Fig. 3 is a plan view partly in section of 110

the bed plate of the machine and parts carried thereby showing the parts in the positions occupied when a label is positioned in readiness to be moved transversely beneath the presser foot, the sewing of the previously transferred label on the garment having just been completed;

Fig. 4 is a similar view showing the parts in the same position, except that the label has been moved beneath the presser foot, so that the sewing of the label on the garment is about to begin;

Fig. 5 is a similar view at the time when one side of the label has been sewed and the next label is about to be cut from the tape;

Fig. 6 is a vertical sectional detail showing the connections for operating the knife whereby labels are severed from the label tape.

Fig. 7 is an enlarged vertical section taken on line 7—7 of Fig. 4.

Referring to the drawings, our invention is shown as applied to a sewing machine having a stationary bed plate 1, a standard 2, having a forwardly extending overhanging portion 3 and a front vertically extending head carried thereby in which is contained the mechanism for operating the needle 5.

The needle is operated in usual fashion which need not be described. In the operation of the machine a shaft 6 is rotated by belt running over a pulley 7 thereon. A shaft 8 is also rotated by connections which need not be described throughout the rotation of the power shaft 6. A disc 9 rotates with shaft 8, this disc carrying various cam grooves with which pins or rollers 30 coact as will be subsequently described.

In the operation of the machine a label is positioned, by means to be described, beneath the presser foot 10. This presser foot is carried by a bracket 11 and comprises a rectangular frame, the needle being adapted to sew alongside the four inner edges of this frame in sewing the label on a garment. During the operation of the machine the presser foot is moved in such manner as to cause the label to be sewed successively about its four edges; the mechanism for effecting such movement is old and accordingly will not be described more than is necessary for an understanding of our invention.

In the operation of the machine a continuous label tape 12 is fed one label length at a time into the machine, the front label is severed and is advanced into position to be accurately positioned beneath the presser foot 10 to be sewed on a garment.

The label tape is shown (Fig. 4) as being wound on a suitable reel 13 supported by a bracket 14 at one side of the machine. The tape is led from this reel into a guideway 15

which is fixedly secured to the adjacent side edge of bed plate 1. Guideway 15 is shown, Fig. 3, as having a side flange 16 thereon, secured to a bracket 17 which is secured to bed plate 1.

The label tape 12, in the form of our invention illustrated, comprises a continuous strip of woven fabric having transverse slits 18 extending part way across the same at approximately uniform intervals, printed matter appearing on each section of tape between a pair of adjacent slits, the individual labels to be formed from the lengths of tape comprised between adjacent slits. The tapes preferably are prepared for use in the apparatus herein described by forming the slits at the same time that the label sections are printed. The slits thus formed will be equally spaced on the tape but in subsequently handling the tape, as explained, a certain amount of variation in the distance between adjacent slits may occur because of stretching of the fabric, etc. Also a certain amount of variation in the spacing of the slits as formed may be permitted, with our invention, the forward feeding of the tape, presently to be explained, enabling the individual labels to be properly presented to the cutting, folding, and sewing mechanism in spite of such variations.

The guideway 15 is positioned with its inner or forward edge slidably resting within a guide portion 19 of a movable member, presently to be described. The fixed guideway 15 is of a width suitable to accommodate the tape and is provided for at least a portion of its length with top flanges 20 which extend over the side edges of the tape to keep the same from buckling. Guide member 15 is also provided with means for preventing backward movement of the tape during operation. This preferably takes the form of a weighted member resting on the tape. As shown, this member preferably takes the form of a metal bar 21 pivoted at its rear or outer end on a pin 22 carried by lugs 23 which extend upwardly from the outer end of guide 15. The rear, or outer, end of the pivoted weight 21 is preferably provided with a lip 24 at the outer side of pivot pin 22, which may be engaged and depressed by the thumb in order to raise weight 21 when the forward end of the tape is first inserted into guide 15. The guide is preferably provided with vertical side flanges 25 between which pivoted weight 21 is mounted.

The tape is fed forwardly through guide 15 by means of a reciprocating arm or pusher member 26 pivoted at its rear end on a horizontal stud 27 carried by the upper end portion of an arm 28, the lower end of which is secured to a rock shaft 29 mounted in vertical flanges of the bracket 17 secured to bed plate 1. Rock shaft 29 is provided

with another upwardly extending arm 30, the upper end of which carries horizontal pin 31 on which is mounted a yoke 32. A horizontal rod 33 is connected to yoke 32 and extends across bed plate 1 to the opposite side of the machine, where connections, presently to be explained, are adapted to cause reciprocation of rod 33 during the operation of the machine.

10 Pusher 26 preferably comprise a strip of metal having a loop at its rear end through which pin 27 extends. For the purpose of adjusting the lengths of pusher 26 the same is preferably made in two parts, namely the 15 pivoted strip 26 and a thin strip 26¹ carried thereby and secured thereto by suitable means such as screws 34 extending through slot 35 in strip 26¹ and into the member 26. The thin strip 26¹ preferably curves 20 slightly downwardly and forwardly and is provided at its forward end with a nose 36 having a smooth forward edge, adapted to enter slits 18 in the tape. The pusher may, of course, be spring pressed downwardly, if 25 desired, but in the form of construction shown the weight of member 26 is sufficient to hold nose 36 in contact with the tape. Shoulders 37 are provided on strip 26¹ at the rear of nose 36 which shoulders will abut 30 against the fabric of the tape at each end of a slit to limit the distance nose 36 enters within a slit during the feeding of the tape.

The height of pivot pin 27 may be made adjustable if desired, by forming this pivot 35 pin as a threaded bolt which is secured in adjusted position within a slot 38 in arm 28. Correspondingly pin 31 may be formed as a bolt adjustably mounted at a desired height in the slot 39 of arm 30. The outer 40 end of rod 33 may be screw-threaded, as shown at 40, and yoke 32 secured in proper position thereon between a pair of adjusting nuts 41. The forward movement of the pusher 26 is limited by an adjustable stop 45 which preferably comprises a screw 42 carried by the flange 16 of bracket 17 which screw is engaged by the forward edge of arm 28.

The horizontal rod 33 is pivotally connected at its opposite end as shown in Fig. 4 to an arm 43 of a bell crank pivoted at 44 to base plate 1. Rod 33 may be provided at its end with a short sleeve member 45 having a tongue 46 which extends between the arms 47 of a short bifurcated member 48, a horizontal pin or screw 49 extending through arms 46 and 47 to constitute a pivotal connection between member 48 and rod 33. A vertical screw 50 extends through the end portion of bifurcated member 48 and into arm 43 of the bell crank to constitute a vertical pivot connection between member 48 and the arm 43. The other arm, 51, of the bell crank pivoted at 44 is pivotally connected to a block 52 by means of vertical

5 pivot pin 53. Block 52 is bifurcated and similar to member 48. A link 54 extends between the arms of bifurcated block 52 and is pivotally connected thereto by a horizontal pin 55.

10 Link 54 is pivotally connected at its opposite end to the lower end of the vertical arm 57 (Fig. 2), of a bell crank pivoted at 58 to a vertical bracket 59 rising from the bed plate 1.

15 The bell crank, referred to, has a horizontal arm 60 which carries a pin 61 which extends into the cam groove 62 of the revolving disc 9. The result of this construction is to reciprocate arm 33 and the pusher or tape feeding device 26, 26¹, at proper timed intervals during the operation of the machine, groove 62 being properly shaped for this purpose.

20 In the operation of pusher 26, 26¹, the same moves outwardly, nose 36 of the pusher sliding rearwardly or outwardly over the face of the tape until the nose 36 reaches its point of extreme outward movement. At this time the nose 36 will be a short distance, such, for example, as one-quarter inch, or three-eighths of an inch to the rear, that is outwardly from, one of the slits 18, this distance varying somewhat if the spacing of the 25 slits is not entirely exact on account of stretching, etc. On the succeeding forward or inward movement of pusher 26, 26¹, nose 36 will slide over the tape until it enters the foremost slit 18, the nose entering the slit 30 against the shoulders 37, the shoulders 37 engaging against the material at the ends of the slit. The pusher then continuing to advance will slide the tape forwardly until arm 28 contacts against stop 42 at which time the pusher will be at its extreme limit of inward movement. A certain 35 amount of lost motion is provided in the device caused by the loose fit of pin 61 in cam slot 62 of disc 9. Accordingly the slit 18 engaged by nose 36 will be positioned exactly at a predetermined point, at the extreme limit of inward movement of the pusher when arm 28 engages stop 42. The pusher will subsequently be retracted from this position leaving the tape in its advanced 40 position with the slit referred to at a definite point which point will be invariably the extreme inward limit of movement of nose 36 regardless of any variation in the spacing of the slits on the tape.

45 The slit thus engaged will in each instance be the one at the rear end of the forward label section of the tape. The front label thus positioned with its rear edge at the predetermined point mentioned will now be cut off and clamped or gripped by a device which will move the same forwardly, that is in the direction of movement of the tape, a further distance into a position from which it may subsequently be transferred, 50 in a direction transverse to its former direction.

tion of movement, underneath the presser foot 10. The devices for carrying out these movements with incidental reference to the mechanisms by which the presser foot is properly moved to cause the sewing of a label around the four sides thereof will now be described.

It should be understood that a label beneath the presser foot is being sewed into position upon a garment at the same time that the label tape is being fed forwardly and the forward label portion thereof moved into position to be fed beneath the presser foot as soon as the sewing of the label then under the presser foot is completed.

Presser foot 10, as stated, is carried by arm 11 which is mounted on a member 63 which is mounted for sliding and pivotal movement on base plate 1. Member 63 is moved back and forth over base plate 1, in a plane substantially at right angles to the guideway 15, at proper times to cause the needle 5 to sew along the two ends 64 of the rectangular opening in the presser foot. Member 63 together with bracket 11 and presser foot 10 are also swung at properly timed intervals about a vertical pivot at the rear of member 63 in order to cause the needle to sew along the front and rear edges 65 of the rectangular opening in the presser foot. Mechanisms for accomplishing these movements of the presser foot are not in themselves part of our invention and the same will be merely referred to briefly.

The forward and back movement of member 63 is accomplished by the coaction of a pin indicated at 66 (Fig. 4) which operates in a cam groove on the inner or back face of cam disc 9. Pin 66 is carried by an arm 67 which is pivoted at its lower end and which is oscillated about its pivot by the movement of pin 66 in its cam groove in disc 9. Arm 67 carries a pin 68 indicated in dotted lines in Fig. 4 which is secured to the upper portion of a vertically extending flanged member 69 which is pivotally suspended at its connection with pin 68. A vertical rod 70 extends through the frame 69 and through the member 63 in which it is mounted, rod 70 carrying a block 71 which is adapted to bear against the front and rear inner surfaces of the frame 69. The oscillation of frame 69 in a vertical plane, about its pivot adjacent its upper end, caused by movement of arm 67 imparted thereto by the engagement of pin 66 in its cam groove, causes pressure to be exerted by the lower part of frame 69 on block 71. The latter as stated is carried by rod 70 which is carried by slide 68, and accordingly the latter will be reciprocated in the direction of its length, at proper times, in accordance with the configuration of the cam groove engaged by pin 66.

The pivotal movement of member 63, referred to, takes place about shaft 70 as a

center. This movement is effected (Fig. 4) by an arm 72 connected at one end to a pin 73 which extends downwardly from member 63 through a suitable slot in the base plate. Arm 72 is connected to an arm 74 of a bell crank pivoted to the under side of the base plate, the other arm of which, 74¹, is slotted. A pin 75 carried by the end of a link 76 engages within the slot of arm 74¹. Link 76 is connected to the lower end of a lever 77 pivoted intermediate its ends to a bracket carried by the base plate. The upper end of lever 77 carries a pin 78, Fig. 4, which engages within cam groove 62 at the outer face of cam disc 9, this being the same cam groove with which pin 61 coacts, as previously described, whereby the movement of the pusher 36 for the label tape is effected. The rotation of the cam disc results through the lever and link connections just described in the oscillation of member 63 about vertical shaft 70 as a center to effect the transverse movements of the presser foot at proper times.

As has been previously stated the forward end of the stationary tape guide 15 rests within a sliding guide member 19 which is axially aligned with the guideway 15. The sliding guide member 19 is slidably mounted in a guiding slot 79 on the face of bed plate 1 and extending beneath the fixed guide member 15. Guideway 19 is part of a transversely movable carriage which carries at the inner or forward end of the guideway 19, a pivoted knife 80. Beyond knife 80 in the direction of movement of the label tape is a pivoted clamping member 81 whereby the forward label section of the tape, cut off by knife 80, is gripped and moved into alignment with presser foot 10.

The carriage comprising slide 19 and the other parts mentioned is given its transverse movement from the pivotal movement of member 63 about its vertical center 70. A link 82 is pivotally connected at one end by pin 83 with member 63. At its other end link 82 is pivotally connected with a lever 84 which is pivoted intermediate its ends at 85 upon the upper surface of the base plate. The opposite end of lever 84 is pivotally connected to a short link 86, the opposite end of which is pivotally connected at 87 to the transversely movable carriage comprising the sliding guideway 19.

With this construction it will be noted that guideway 19 together with pivoted knife 80 and the clamping member 81 will move transversely across the bed plate during the swinging movement of member 63 across the bed plate and in opposite direction thereto.

The clamping member 81 is pivotally carried by an arm 88, the rear end of which is secured to a short horizontal transverse rock shaft, indicated at 89, the rear end of

- knife 80 being secured to the same rock shaft, (Figs. 5 and 6). Knife 80 and clamping member 81 are swung downwardly, together, at the proper times for the forward 65
 5 label to be cut from the tape by the knife and to be gripped by the clamping device. This operative movement of the knife and clamping member is caused by a horizontal rod 90 which extends forwardly underneath 70
 10 the bed plate from a fixed connection at 91 with member 63, Fig. 4, the lug 91 of members 63 extending downwardly through a suitable slot in the bed plate. Rod 90 is pivotally connected at its forward end to
 15 a downwardly extending arm 89¹ secured to the rock shaft 89. Accordingly, as member 63 begins to slide to the right, referring to Figs. 3, 4 and 5, at the time when knife 80 is properly positioned with respect to the 80
 20 label tape, the knife will be operated by the connections referred to, to cut off the forward label section of the tape, clamping device 81 at the same time gripping the severed forward label section. 85
 25 The knife and the clamping member will again be raised when member 63 and the presser foot 10 begin to move to the left, referring to Figs. 3, 4 and 5, at which time the transversely movable carriage, carrying 90
 30 the knife and the clamping member for the forward label will have been positioned in alignment with the presser foot, as is shown in Fig. 3. 95
 A spring finger 92 is carried by an arm 93, pivoted at 94 to the transversely slidable carriage. This arm is provided, at its opposite or inner end, with a slot 95, in which 100
 35 is positioned a vertical pin 96 on the horizontal frame 63 by which the presser foot is carried. Accordingly, arm 93 and spring 92 will be swung transversely of the base plate between the positions shown in Figs. 5 and 3 as pin 94 moves with the transversely moving carriage and pin 96 swings 105
 40 in the opposite direction, with the result of moving the spring member 92 forwardly to press firmly upon the severed front label, at the time when the label has been aligned with the presser foot. The spring will accordingly be in position to hold the label 110
 45 when clamping member 81 has been raised, (Figs. 1 and 3). 115
 The transversely travelling carriage which carries the clamping member 81 additionally 120
 50 includes the surface 97, (Figs. 1 and 7), in alignment with the sliding guideway 19, this being the surface upon which the severed front label is clamped by member 81. This surface is provided with a pair of parallel 125
 55 scored lines 98 which extend transverse to the line of movement of the label tape through guideways 15 and 19. Clamping member 81 is provided with downwardly extending end flanges 99 which are adapted
 60 to register with the grooves or scored lines 98. When, accordingly, the clamping member swings downwardly upon the severed label it will not only clamp the same to the surface 97, but will also serve to bend the end portions of the label somewhat upwardly, by pressing the portions of the label adjacent to the ends into the grooves 98, as stated. The ends of the label are thus bent up so as to facilitate the folding over of the same when the label is inserted beneath the 75
 65 presser foot. 70
 As stated, one label is sewed to a garment beneath presser foot 10 during the time that the label tape is being fed forwardly, the front label section cut therefrom, and the severed label positioned in alignment with the presser foot in the position shown in Fig. 3. At this point in the operation the machine is stopped by the operation of a belt shifter 100, Fig. 2, which shifts the power belt from the fixed pulley 7 to the loose pulley 101 on the power shaft 6. The operation of the belt shifter is controlled by a pin 102 operating in groove 103 on the face of cam disc 9, this pin being connected to a suitable lever arm (not shown) connected to operate the belt shifter. A lateral recess (not shown) opens into groove 103 and pin 102 moves laterally into the same once each revolution of disc 9, when this lateral recess comes into alignment with pin 102. The machine is accordingly stopped at this point which corresponds with the moment when the label beneath the presser foot has been completely sewed to a garment. 100
 When the machine stops the operator will withdraw from beneath the presser foot the garment on which the label was sewed and will then position another garment beneath the presser foot in position to have the next label sewed thereon. The presser foot may be lifted up in the usual manner to permit this change of work. The article being positioned upon the forward surface 104, which constitutes a forward extension of the movable member 63, and the presser foot being repositioned thereon, the label which is now held to the rear of the presser foot beneath the spring finger 97 is advanced forwardly 105
 70 into sewing position. This is accomplished in the form of invention illustrated by means of a foot treadle which is connected by chain 105 (Fig. 1) to the arm 106 pivoted at 107 at the rear of the machine. Arm 106 is pivotally connected at its forward end to an arm 108 of a bell crank pivoted at 109 to the bracket 110. Arm 106 is normally held in raised position by a spring 111 secured to the bracket 112. 110
 The bell crank pivoted at 109 is provided with a downwardly extending arm 113, Fig. 2, carrying a pin 114 which was shown in Figs. 2 and 4, extends laterally between a 115
 75 120
 80 125

pair of upwardly extending arms 115, which are rigid with a slide 116 slidably mounted on the base plate at the side of member 63.

This slideable member 116 is provided at 6 its forward end with jaws 117 and a transverse rear seating surface 118 (Fig. 5). When member 116 is moved forwardly by the operation of the foot treadle, as stated, the jaws 117, 118, will slide beneath spring 10 finger 92 and will position the label beneath the presser foot jaw or surface 118 pushing against the rear edge of the label to push it forwardly, while jaws 117 serve to engage the side edges of the label to hold it smooth, 15 jaws 117 and 118 being shown in their forwardly extended position in Fig. 4.

As the label moves forwardly beneath the presser foot its bent up end edges will be folded over completely by passing beneath 20 the bevelled inner edges of members 119, and will then move beneath the overhanging ends of members 120, secured upon the support 104, the under surfaces of which are provided with serrations to hold the label 25 against backward movement when slide 116 moves back. The label will thus be positioned beneath the article to which it is to be sewed upon plate 104 and in proper alignment beneath the rectangular opening in 30 presser foot, 10.

A second foot treadle (not shown) is now depressed by the operator, this treadle operating through chain 121 connected to pivoted arm 122, Fig. 2, which will serve to 35 swing belt shifter 100 to return the power belt to the fixed pulley 7 and again start the machine in operation.

The operation of the apparatus is briefly as follows: a label tape having been placed 40 on reel 13 is inserted into guide 15 beneath the pivoted weight 21, far enough so that the foremost slit in the tape, that is, the slit at the rear of the foremost label section of the tape, will be positioned on guideway 15 45 a short distance in front of the nose 36 of pusher 26 when the latter is in its rearmost position. The machine being started in operation the slit engaged by nose 36 will be advanced to the predetermined point previously referred to, this point being determined by the engagement of arm 28 with stop 42. The point referred to is the position occupied by the knife 80 in Fig. 5. Knife 80 will be positioned in alignment 50 with this point after pusher 26 has receded somewhat therefrom on its backward or outward stroke. The knife will, when positioned at this point, operate to cut off the front label section, while at the same time 55 the gripping member 81 moves downwardly to grip the severed front label and to somewhat bend the ends thereof upwardly. The travelling carriage carrying the knife and gripping member and the slideable guideway 60 19 will then be moved away from pusher 26

into the position shown in Fig. 3. The machine now stopping, because of the shifting of the driving belt from fixed pulley 7 to the loose pulley 101, the operator will depress a foot treadle, as stated, to cause the operation of arm 106 and the forward movement of slide 116 to position the severed label beneath the presser foot with its ends folded over in position to be sewed upon a garment which has previously been inserted by hand beneath the presser foot. The position of the parts after the label has thus been moved transversely beneath the presser foot is shown in Fig. 4.

The operator now depresses the other foot treadle to start the machine again in operation, whereupon the label thus positioned beneath the presser foot will be sewed to the garment while at the same time the next forward label section of the tape will be moved 75 forwardly, cut off and moved into the position shown in Fig. 3 at the moment when the sewing of the label beneath the presser foot is completed.

The timing of the various parts will be 80 as follows. The needle 5 is shown in Fig. 3 in the position occupied when the sewing of a label is about to commence. The pusher 26 has started to move forwardly shortly before this time, and has already engaged its nose 85 36 with the foremost slit 18 of the tape.

Starting with this position, the presser foot and parts connected therewith swing to the right about the vertical center 70, which is to say that the presser foot moves in the 100 direction of feed of the label tape, or upwardly of the drawings, Figs. 3, 4 and 5. Accordingly, the right-hand edge of the opening in the presser foot moves past needle 5 until the needle has sewed along a side 105 edge of the label from the position of the needle shown in Fig. 3 to its position shown in Fig. 5.

During this relative movement of the needle from what may be termed the first 110 corner of the rectangular opening in the presser foot to what may be termed the second corner, the pusher 26 will advance the slit in the tape engaged thereby to its limit of forward movement and will have started 115 somewhat on its backward movement into the position shown in Fig. 5. During this movement also the movable carriage comprising sliding guideway 19, knife 80, etc., will be moving in opposite direction to that of the presser foot because of the reversing connection provided by lever 84 and connected parts interposed between the sliding guideway 19 and member 63. Accordingly, 120 this travelling carriage moves in opposite direction to that of the forward feed of the tape, that is downwardly of the drawing in Figs. 3 and 5. Knife 80 will reach its furthest out position, in alignment with the slit 125 18 which has been positioned at the point of 130

extreme forward movement of pusher 26, when the relative movement between needle 5 and presser foot 10 has positioned needle 5 above the second or lower right-hand corner 5 of the rectangular opening in the presser foot, as shown in Fig. 5.

The presser foot now moves to the right, referring to the drawings Figs. 3 to 5, because of the coaction of pin 66 in its cam 10 groove on the back or inner face of disc 9, as shown in Fig. 4. The needle 5 will accordingly be brought to the lower left hand corner of the label, or of the opening in the presser foot, referring to the figures indicated, or what I may term the third corner. During this movement of the presser foot 15 knife 80 will move downwardly to cut off the front label section from the tape and member 81 will move downwardly to clamp the severed label section in position and to bend up its ends somewhat, as stated. The knife and gripping member will, of course, have no movement of translation across the bed plate 20 during this time, but the pusher 26 will continue to move back or outwardly towards its 25 outermost position during this time.

The member 63 now swings to the left about its pivot 70 so that needle 5 will sew along the outer edge of the label, moving 30 from the lower left-hand to the upper left-hand corner, or from corner three to corner four. Pusher 26 completes its backward movement during this time, which positions 35 nose 36 a short distance back of, or outwardly from, the next slit in the tape. Sliding guideway 19 and connected parts move in opposite direction to that of the presser 40 foot during all of this time, so that the severed label gripped between member 81 above the label and the travelling surface 97 beneath the label will be moved into the position 45 shown in Fig. 3, arriving in such position at the moment when needle 5 is positioned in the fourth, or upper left-hand corner of the label which is being sewed. Pusher 26 starts on its next forward movement 50 just before needle 5 reaches the upper left-hand corner of the label, in the relative movement between the needle and the presser foot.

The presser foot and connected parts now move to the left, referring to Figs. 3 and 5, to bring the needle into its initial position at the upper right-hand corner at which time 55 the sewing of the label is completed. During this movement pusher 26 is advancing somewhat. The travelling carriage comprising slideway 19 is stationary but the sliding movement to the left of member 63 causes 60 knife 80 to be swung upwardly about its pivot 89 and the clamping member 81 to be swung upwardly.

The clamping spring 92, Figs. 1 and 5, is 65 swung forwardly over the front label section which is clamped by member 81, as the latter

reaches the position shown in Fig. 3. The arm carrying this spring, pivoted at 94 to travelling carriage 19, will swing from its position shown in Fig. 5 to the position shown in Fig. 3, while needle 5 is sewing along the edge of the label under the presser foot from the lower left to the upper left-hand corner, at which time the spring 92 has moved into position over the label to hold the latter when member 81 rises. 70

The label beneath the presser foot having now been completely sewed about its edges to the garment, the machine will be automatically stopped, the operator will remove the garment with the label sewed thereon 80 and will position another garment beneath the presser foot whereupon he will operate the foot treadle to transfer the label positioned beneath spring 92 into position to be sewed to the garment and will then immediately start the machine again in operation, as has been described. 85

It should be understood that the invention is not limited to the exact details of construction which have been particularly described, otherwise than as is indicated by the 90 accompanying claims.

It will be noted that while the labels have been described as being sewed to the under side of the garment, they may be sewed to the upper side of the garment, with suitable modification of the apparatus. In this case the ends of the label which has been cut off from the tape will be bent downwardly, instead of upwardly, as has been described 95 herein. 100

What we claim is:

1. In a device of the character described, the combination of means for guiding forwardly a continuous label tape provided at intervals with transverse slits, feeding mechanism, comprising a reciprocating member arranged to slide forwardly along the tape periodically in contact therewith, from a point appreciably to the rear of a slit, regardless of stretching of the tape, engage the slit, advance the slit to a predetermined point, and then move back to its starting point, means for severing the tape along the line of said slit at said predetermined point, 110 after the slit has been positioned at such point, and means for gripping the severed label in advance of said slit and moving the same, while gripped, at an angle to the direction of movement of said severing means through a predetermined distance into position for a further operation to be conducted thereon. 115

2. In a device of the character described, the combination of means for guiding forwardly a continuous label tape provided at intervals with transverse slits, feeding mechanism, comprising a reciprocating member arranged to slide forwardly along the tape periodically in contact therewith, from a 120

point appreciably to the rear of a slit regardless of stretching of the tape, engage the slit, advance the slit to a predetermined point, and then move back to its starting point, means for severing the tape at a fixed point intermediate the forward label and the next label thereto, after said slit and tape have been advanced by said reciprocating member, and means for moving the severed forward label at an angle to the direction of movement of said severing means, into a fixed position for a further operation to be conducted thereon.

3. In a device of the character described, the combination of means for guiding forwardly a continuous label tape provided at intervals with abutment means, feeding mechanism, comprising a reciprocating member arranged to slide forwardly along the tape periodically in contact therewith, from a point appreciably to the rear of an abutment means, regardless of stretching of the tape, engage the same, advance the same to a predetermined point, and then move back to its starting point, a tape cutting device, means for reciprocating the same lengthwise of the tape relative thereto, and means for operating the same, to sever the tape along the line of said abutment means at said predetermined point, after the abutment means has been positioned at such point and said reciprocating feeding member has been retracted from said point.

4. In a device of the character described, the combination of means for guiding forwardly a continuous label tape provided at intervals with transverse slits, feeding mechanism, comprising a reciprocating member arranged to slide forwardly along the tape periodically in contact therewith, from a point to the rear of a slit, engage the slit, advance the slit to a predetermined point, and then move back to its starting point, reciprocating cutting and label-moving means, means for moving said means in opposite direction to that of said tape, from a starting position in advance of the tape to align the said cutting means with a point intermediate the first two labels on the tape and then in reverse direction to said starting position, and means for causing said cutting means to cut off the forward label and said label moving means to firmly grip the severed label, to move the same therewith to its said starting position.

5. In a device of the character described, the combination of means for guiding forwardly a continuous label tape provided with transverse abutment means at approximately uniform intervals, between the individual label portions of the tape, feeding means, comprising a member arranged to move forwardly along the tape in contact therewith from a point appreciably to the rear of the abutment means immediately to

the rear of the front label portion regardless of stretching of the tape, engage the same, advance the same to a predetermined point and then move back to its starting point, means for severing the tape intermediate the first and second label portions, and means for moving the severed forward label further forward into a fixed position for a further operation to be conducted thereon.

6. In a device of the character described, combination of means for guiding forwardly a continuous label tape provided with transverse abutment means at approximately uniform intervals, between the individual label portions of the tape, and feeding means comprising an upwardly extending arm, a feeding arm pivoted thereto with its free end bearing at all times on the tape, means having loit motion, comprising a cam and roller coacting therewith, and connections to said first named arm for moving said first named arm back and forth to cause the end of said arm to engage an abutment means on the tape each stroke and advance the same, and a positive stop engaged by said first named arm to define the end of the forward stroke of said feeding arm.

7. In a device of the character described, the combination of means for guiding forwardly a continuous label tape provided with transverse abutment means at approximately uniform intervals, between the individual label portions of the tape, a reciprocating pusher having a smooth edge arranged to slide along the tape in contact therewith from a point to the rear of one of said abutment means, engage and advance the same to a predetermined point, and then move back to its starting point, vertically acting means for severing the tape at said predetermined point after said pusher has moved back therefrom, means movable as said severing means operates to grip the label section in advance of said severing means, and means for drawing said gripping means and severed label therewith horizontally into a fixed position.

8. In a device of the character described, the combination of a fixed frame member, a carriage comprising a guideway member slidably mounted thereon, a stationary guideway in alignment with said slideable guideway, with its forward end resting thereon, said guideways adapted to receive a label tape provided with transverse abutment means at approximately uniform intervals, a reciprocating feeding member having a smooth edge arranged to slide along the tape on said stationary guideway from a point to the rear of one of said abutment means, engage and advance the same to a predetermined point, means carried by said carriage for severing the tape, means for advancing said carriage towards said tape

- feeding member to align said severing means with said predetermined point after said feeding member has moved back therefrom, and to thereafter return said carriage, away 5 from said feeding member, means for operating said severing means at said predetermined point, and means for gripping a severed label on said carriage as the latter returns, away from said tape feeding member.
- 10 9. In a device of the character described, the combination of a fixed frame member, a carriage comprising a guideway member slidably mounted thereon, a stationary guideway in alignment with said slidable 15 guideway, with its forward end resting thereon, said guideways adapted to receive a label tape provided with transverse abutment means intermediate the individual label sections thereof, a reciprocating feeding member arranged to slide along the tape on said stationary guideway from a point to the rear of one of said abutment means, and to engage and advance the same to a predetermined point, a knife carried by said carriage, means for advancing said carriage, in opposite direction to that of the tape, to align said knife with a point on the tape, on said slidable guideway, intermediate the front label section and the next label section, 25 after said abutment means has been positioned at said predetermined point, and to thereafter move said carriage in opposite direction, and means for causing said knife to sever the tape when it is so aligned.
- 30 35 10. In a device of the character described, the combination of means for guiding forwardly a continuous label tape provided with transverse abutment means intermediate the individual label sections, a travelling 40 carriage onto which the tape is fed from said guiding means, a knife carried by said carriage, a reciprocating feeding member above said guiding means, means for operating said feeding member, to slide the same along 45 the tape from a point to the rear of one of said abutment means, to engage and advance the latter to a predetermined point, and to then retract said member over the tape, means for moving said carriage in opposite 50 direction to that of the tape during the ad-
- vance of the latter and for an interval after said feeding member starts to retract, to align said knife with said predetermined point, for then holding the carriage stationary for an interval and for then moving it in 55 opposite direction, and means for operating said knife at said predetermined point while said carriage is stationary.
11. In a device of the character described, the combination of means for sewing a label 60 about the edges thereof to an article, means, operable while a label is being sewed, for feeding forward a label strip having abutment means between individual label sections thereof, to align one of said abutment 65 means with a predetermined point, a knife, means for automatically operating the same to cut off the front label section when said abutment means is so aligned, label gripping and transferring means, means for moving 70 the same in reverse direction to that of said strip feeding means, while the latter is moving forwardly, to align the same with the forward label when the latter is severed, to thereafter move said label into alignment 75 with said sewing means, and means for moving said label laterally into sewing position, when the previously sewed label and article are removed.
12. In a device of the character described, the combination of means for feeding forwardly a label tape, to position a point on the tape intermediate the first two label sections thereof periodically at a predetermined 80 fixed position, a carriage carrying a knife 85 and label gripping means, and means for moving said carriage in a different direction to that of the tape, substantially parallel thereto, while the tape is moving forwardly, to position said knife at said predetermined 90 position after said intermediate tape point has there come to rest and to position said gripping means above the forward label section, and for thereafter moving said carriage in another direction.

In testimony whereof we have signed our names to this specification.

JULIUS M. REIS.
EMIL F. BUSINGER.
